UNITED STATES PATENT OFFICE

JULIUS C. CHRISTIANSEN, OF NEW YORK, N. Y.

REGULATING DEVICE

1,065,216.

Specification of Letters Patent. Patented June 17, 1913.

Application filed December 14, 1911. Serial No. 668,673.

To all whom it may concern:

Be it known that I, JULIUS C. CHRISTIANSEN, a subject of the Emperor of Germany, residing at New York, in the county of New York and State of New York, have invented certain new and useful Improvements in Regulating Devices, of which the following is a specification, reference being had to the accompanying drawing.

19 The invention is designed primarily to provide novel means for controlling the steering device, such as the rudder of vessels for navigating water and air.

25 Inasmuch as the invention resides chiefly in the operating mechanism it is contemplated within the purview of the invention to apply the same generally for operating movable parts.

20 The invention consists of the novel features, details of construction and combination of parts, which hereinafter will be more particularly set forth, illustrated in the accompanying drawing, and pointed out in the appended claims.

25 Referring to the drawing, forming a part of the specification, Figure 1 is a view in elevation partly in diagram of a control shown in connection with fore and aft rudders for steering a vessel or air craft. Fig. 20. 2 is a view similar to Fig. 1 as seen from above. Fig. 3 is a detail view of the intermediate portion of the longitudinally movable rod and the inner ends of the alining parts of the hollow shaft which are connected by a segment and an offstanding portion.

35 Corresponding and like parts are referred to in the following description, and indicated in all the views of the drawing, by the same reference characters.

40 The numeral 1 designates a hollow shaft, which is mounted in bearings 7 and comprises parts which are connected by means of a segment 2 and an offstanding portion 24. A pulley 16 is fast to one end of the

45 hollow shaft 1 and a cross bar 8 is secured to the opposite end of such shaft and has a plane 12 hinged or pivotally connected thereto. The segment 2 comprises parallel members between which operates a lever 14

50 which is pivoted at 15 to the offstanding portion 24. A weight 13 is connected with the lower end of the lever 14 to normally hold the same in a vertical plane. A rod 5 is mounted within the shaft 1 in such a

55 manner as to move longitudinally therein and to relatively turn. The rod 5 has a

cross bar 6 at a point between the ends of the shaft 1 connected by the parts 2 and 24. This cross bar 6 is slotted longitudinally to receive the operating lever 14. The ends 60 of the rod 5 extend beyond the extremities of the shaft 1. A link 9 connects one end of the rod 5 with an arm 11 projecting laterally from the plane 12. The opposite end of the rod 5 is pivotally connected to a lever 65 21, as indicated at 23, said lever being fulcrumed at 22. Longitudinal movement of the rod 5 is effected by means of the operating lever 14 and said rod is held in the adjusted position by means of a latch, not 70 shown, mounted upon the lever 14 in the usual manner and adapted to engage teeth of the segment 2. A segment 3 is supported by means of a rod 4 which is arranged at a right angle to the rod 5. The segment 3 75 comprises parallel members between which the operating lever 14 passes.

80 The shaft 1 is adapted to be turned about its axis by means of the lever 14 and is held in the adjusted position by means of the segment 3 and a latch, not shown, mounted upon the lever 14. Rotary movement of the shaft 1 causes a corresponding movement of the cross bar 8 and pulley 16. The plane 12 connected to the cross bar 8 moves therewith into the required angular position and said plane may be adjusted angularly with reference to the length of the shaft 1 by longitudinal movement of the rod 5 through the instrumentality of the link 9 and arm 85 11. Either angular adjustment of the plane 12 may be separately effected or both angular adjustments may be effected by a simultaneous turning of the shaft 1 and a longitudinal movement of the rod 5.

90 A shaft 25 is mounted in bearings 7 preferably in line with the shaft 1 and has a cross bar 8 fast thereto. A plane 12 is hinged or pivoted to the cross bar 8 and has oppositely extending arms 10 to which 100 flexible connections 20 are attached, said connections being made fast to opposite ends of the lever 21. Relative lateral adjustment of the plane 12 is effected by a movement of the lever 21 when the rod 5 is moved longitudinally. A pulley 18 is secured to the shaft 25. Guide pulleys 17 are located at the sides of the shafts 1 and 25. A flexible connection 19 is passed around the pulleys 16 and 18 one or more times and over the pulleys 17. Rotation of the shaft 1 causes a 105 corresponding rotary movement of the shaft 25.

25, whereby the plane 12 connected with such shaft is moved angularly. In the event of the parts to be operated, such as the planes 12, the same may be moved oppositely 5 or in the same direction according to the result to be accomplished and in the event of such parts 12 consisting of fore and aft rudders of a vessel or air craft the same may be quickly started which is of vital consequence when the invention is applied to the rudders of air craft which are required to be directed vertically as well as laterally in order to rise or descend or to move to the right or left.

15 From the foregoing description, taken in connection with the accompanying drawing, the advantages of the construction and of the method of operation will be readily apparent to those skilled in the art to which 20 the invention appertains, and while I have described the principle of operation of the invention, together with the device which I now consider to be the best embodiment thereof, I desire to have it understood that 25 the device shown is merely illustrative, and that such changes may be made when desired as are within the scope of the claims appended hereto.

Having thus described the invention what 30 is claimed as new, is:—

1. In combination concentric members, the

one rotatable and the other movable longitudinally, a cross bar attached to the rotatable member, a swinging member pivotally connected to the cross bar, connecting means 35 between the swinging member and the longitudinally movable member, an operating lever having connection with the two members to effect independent or simultaneous movement thereof, and means for securing 40 the operating lever in the adjusted position.

2. In combination concentric members, the one being rotatable and the other movable longitudinally, an operating lever having connection with such members and adapted 45 to move them independently of each other, a second shaft rotatably mounted, a member hingedly connected to the second shaft, connecting means between the second shaft and the before mentioned rotatable member for 50 causing both to turn together, a lever connected with the longitudinally movable member, and connecting means between such lever and the member hingedly connected to the before mentioned second shaft. 55

Signed at the city of New York, county of New York, and State of New York.

JULIUS C. CHRISTIANSEN.
